US00D911435S

(12) United States Design Patent (10) Patent No.: US D911,435 S
 Carroll et al. (45) Date of Patent:  Feb. 23, 2021

(54) TYPEFACE
 (71) Applicant: Turkcell İletişim Hizmetleri A.S.,
 İstanbul (TR)
 (72) Inventors: Paul Carroll, New York, NY (US);
Peter Eric Arnell, New York, NY (US)
 () Term: 15 Years
 (21) Appl. No.: 35/507,972
 (22) Filed: May 30, 2019
 (80) Hague Agreement Data
 Int. Filing Date: May 30, 2019
 Int. Reg. No.: DM/203731
 Int. Reg. Date: May 30, 2019
 Int. Reg. Pub. Date: Dec. 6, 2019
 (51) LOC (13) Cl. 18-03
 (52) U.S. Cl. D18/24
 USPC D18/24
 (58) Field of Classification Search
 USPC D18/24-33
 CPC B41B 1/02
 See application file for complete search history.
